UNITED STATES PATENT OFFICE

143,288

DESIGN FOR AN ESCUTCHEON FOR SINK FITTINGS

Henry Dreyfuss, New York, N. Y., assignor to
Crane Co., Chicago, Ill., a corporation of Illinois

Application April 26, 1945, Serial No. 119,249

Term of patent 14 years

(Cl. D91—3)

To all whom it may concern:

Be it known that I, Henry Dreyfuss, a citizen of the United States, residing at New York, in the county of New York and State of New York, have invented a new, original, and ornamental Design for an Escutcheon for Sink Fittings, of which the following is a specification, reference being had to the accompanying drawing, forming part thereof.

Fig. 1 is a top view of the escutcheon for sink fittings embodying my design.

Fig. 2 is a front view thereof.

Fig. 3 is a side view of the same.

I claim:

The ornamental design for an escutcheon for sink fittings, substantially as shown.

HENRY DREYFUSS.
